UNITED STATES PATENT OFFICE

WILLIAM TOWNSEND, OF CHICAGO, ILLINOIS, ASSIGNOR TO THE CONNERSVILLE BLOWER COMPANY, INC., OF CONNERSVILLE, INDIANA, A CORPORATION OF INDIANA

UNLOADING VALVE

Application filed October 27, 1927. Serial No. 229,089.

In the use of blowers of the lobed impeller type, to provide and maintain a fluid pressure within a system, delivery from which fluctuates through wide ranges or is, through 5 considerable periods, much less than the capacity of the blower, it is desirable that the resistance to forward movement of the blower be reduced as much as possible.

The object of my present invention is to 10 provide automatic mechanism, dependent upon the fluid pressure in the delivery system, for automatically controlling delivery of fluid pressure to the delivery system.

The accompanying drawings illustrate my 15 invention.

Fig. 1 is a side elevation, in partial vertical section, of an apparatus embodying my invention; Fig. 2 is a fragmentary elevation, on an enlarged scale of the mechanism for 20 controlling the position of the by-pass valve; Fig. 3, a plan on line 3, 3 of Fig. 1; Fig. 4, a fragmentary plan of the barrel cam and adjacent parts; Fig. 5, an axial section of a modified form of by-pass valve; Fig. 25 6, a section of another modified form of by-pass valve; Fig. 7, a view similar to Fig. 1, of a modified form, and Fig. 8 a fragmentary modification of the construction shown in Fig. 7.

30 In Figs. 1 to 3 inclusive 10 indicates the blower which may conveniently be an ordinary blower of the interdigitated rotary lobed impeller type the shaft 11 of one impeller being projected and provided with a pinion 12, the purpose of which will appear. Blower 10 is provided with an inlet 13 and an outlet 14 delivering through a check valve structure 15 to the delivery system 16 from which suitable outlets will be provided.

40 Arranged as a by-pass between outlet 14 and inlet 13, around the blower 10, is a system of piping 17 in which is arranged a suitable valve mechanism 18 which will control the flow or possibility of flow through 45 the by-pass piping.

Meshing with pinion 12 is a gear 20 to which is secured a barrel cam C having a cylindrical portion 21, a smaller cylindrical portion 22, and a connecting portion 23 which connects portions 21 and 22. Riding

cam C is a roller 24 which is rotatably and slidably mounted on a rod 25 carried in the fork 26 of a lever 27 pivoted at 28 on the blower casing. Lever 27 is connected by a link 29 and lever 30 with the stem 31 of 55 valve 18.

Rod 25 is arranged parallel with the axis of cam C and roller 24 is shifted along rod 25, parallel with the axis of cam C by means of a yoke 35 connected by a link 36 with a lever 37 actuated by the bell 38 of a manometer 39 the interior of which is connected by pipe 40 with the delivery system 16.

The operation is as follows:

When the apparatus is started and there 65 is no pressure within system 16 bell 38 will be in its lowest position and roller 24 will be riding the small diameter portion 22 of cam C beyond portion 23 of said cam (the extreme opposite position from that shown 70 in Fig. 2). In this position valve 18 is closed and there is no flow through the by-pass pipe 17, the entire delivery of the blower passing through the check valve 15 into system 16. As the pressure in system 75 16 rises roller 24 will be shifted parallel with the axis of cam C so that intermittently portion 23 of that cam will come beneath said roller and thus open valve 18 momentarily thereby permitting a portion 80 of the discharge of the blower to be bypassed around the blower through pipe 17 and thus momentarily relieving the load on the blower.

Whenever full pressure has been attained 85 in system 16 and demand therefrom has momentarily ceased, roller 24 will have been shifted to the position shown in Fig. 2 where it is riding continuously upon the cylindrical portion 21 of cam C. In this 90 position valve 18 is open continuously and the blower is relieved of all load excepting the comparatively small resistance to flow through the by-pass pipe 17.

The precise ratio of rotation of cam C to 95 rotation of the blower impellers is not material and can be made to suit the conditions of the particular installation. In practice I have found that it is generally advisable 100

to rotate cam C somewhat slower than the impellers.

In Fig. 5 I have shown an unbalanced valve 50, of cup form as a substitute for valve 18, said valve being a reciprocating one. In this form the stem 51 will be connected to lever 30.

In Fig. 6 the cup valve 60 is provided at one side with a notch 61 and this valve is 10 rotatably and slidably mounted in a cylinder 62 the wall of which is provided with a notch 63 with which notch 61 may register more or less depending upon the speed of rotation of the valve 60 and its axial position within its cylinder. The stem 64 of valve 60 is splined within a gear 20' meshing with a pinion 12' rotated by the blower. Stem 64 is connected to a yoke 65 carried by a rod 66 which, in turn, will be suitably 20 connected to lever 27, the arrangement being such that the axial position of cup 60 in its cylinder 62, and consequently the degree of registration between notches 61 and 63, will be dependent upon the pressure in the 25 manometer 39.

It will, of course, be readily understood that the piping 17 beyond the valve 18 may lead to atmosphere or some other point instead of leading to the inlet side of the structure and in the claims the term by-pass is used in its broader significance and is not intended to be limited to a structure which returns to the inlet side of the system.

In Fig. 7 a belt 70 leading from shaft 11, 35 operates a crank disc 71 to which is connected a reach rod 72 connected to a bell crank 73 one arm of which is provided with a hook 74 adapted to engage a pin 75 on a lever 76 which is connected to the rod 31 of valve 18, the arrangement being such 40 that valve 18 will be alternately opened and closed by the rotation of crank disc 71, the relative time of open and closed positions being determined by the knock off block 80. 45 It will, of course, be understood that disc 71 might be independently rotated if desired.

The relative time of open and closed operations of valve 18 may also be modified by the adjustment of the cam 80 movable into 50 and out of the path of movement of the finger 81 of hook 74. Block 80 may be automatically positioned by means of a reach rod 82 actuated by the diaphragm of a diaphragm chamber 83 which chamber is 55 connected by pipe 84 with the air delivery pipe 16. Cam 80 may be manually adjusted by means of an arm 87 and segment 88, if desired.

A dash pot 90 dampens the closing of 60 valve 18.

I claim as my invention:

1. The combination of a fluid-pressure producer for a delivery system supplied thereby, a valved by-pass for the discharge 65 of said producer, means synchronized with

said producer for opening and closing said valve, and pressure-controlled means under the influence of pressure in the delivery system for determining the period of valve opening.

2. The combination of a fluid-pressure producer for a delivery system supplied thereby, a valved by-pass for the discharge side of said producer, pressure-controlled means under the influence of pressure in the delivery system, and means synchronized with the producer, both said means connected to and acting upon the valve to determine the extent and duration of its opening.

3. The combination of a fluid-pressure producer for a delivery system supplied thereby, a valved by-pass for the discharge side of said producer, a cam synchronized with the producer, an element actuated by said cam, means controlled by pressure in the delivery system for shifting said element relative to the cam, and connections between the cam-actuated element and valve.

4. The combination of a fluid-pressure producer for a delivery system supplied thereby, a valved by-pass for the discharge side of said producer, a cam synchronized with the producer, and means controlled by pressure in the delivery system for varying the effect of said cam on the valve.

5. The combination of a fluid-pressure producer for a delivery system supplied thereby, a valved by-pass for the discharge side of said producer and mechanically actuated means for regularly recurrently opening and closing said valved by-pass and pressure controlled means under the influence of pressure in the delivery system for modifying the amplitude of the recurrent opening periods.

6. The combination of a fluid-pressure producer for a delivery system supplied thereby, two independent discharge outlets for said producer, one to be connected to the delivery system and the other to form a by-pass away from such system, a valve in said by-pass for controlling outflow from the producer through said by-pass, and mechanically-actuated means for recurrently manipulating said valve to vary outflow through the by-pass.

In witness whereof, I, WILLIAM TOWNSEND, have hereunto set my hand at Chicago, Ill., this 21st day of October, A. D. one thousand nine hundred and twenty-seven.

WILLIAM TOWNSEND.
